UNITED STATES PATENT OFFICE.

ALEXANDER RODGERS AND GILBERT MEE, OF MUSKEGON, MICHIGAN.

ELEVATED RAILWAY.

SPECIFICATION forming part of Letters Patent No. 414,825, dated November 12, 1889.

Application filed January 23, 1889. Serial No. 297,307. (No model.)

To all whom it may concern:

Be it known that we, ALEXANDER RODGERS and GILBERT MEE, citizens of the United States, residing at Muskegon, in the county 5 of Muskegon and State of Michigan, have invented certain new and useful Improvements in Elevated Railways; and we do declare the following to be a full, clear, and exact description of the invention, such as will enable 10 others skilled in the art to which it appertains to make and use the same, reference being had to the accompanying drawings, and to the letters and figures of reference marked thereon, which form a part of this specification.

15 This invention relates to certain improvements in the construction of elevated railways and the devices for operating the same, the whole being especially designed to furnish a means for the transportation of saw- 20 logs or other timber.

In obtaining timber suitable for sawing into lumber it is found necessary to go back some distance from the streams upon which said timber is floated to the mills. In some parts 25 of the country this has become necessary on account of the timber near the streams having been already cut, and in others, especially in the States bordering upon the Gulf of Mexico, by reason of the swampy nature 30 of the banks for a considerable distance inland. To reach this distant timber, it has been found necessary to build railways of greater or less length, as the construction of ordinary roads and cost of transportation of 35 teams over them would greatly increase the cost of the lumber.

The object of this invention is therefore to furnish a railway that may be cheaply constructed in a wooded or swampy country and 40 that shall enable the operator to transport his timber quickly and at low cost.

To accomplish these objects we construct the superstructure of trestle-work, the uprights of which may be round poles, their upper ends connected by cross-pieces bolted to the same. At a suitable distance below these cross-pieces are placed two (one on each side) pieces of timber, their outer ends bolted to the uprights and their inner contiguous ends 45 supported by a rod from the upper cross-piece. These trestles, being erected at proper distances apart along the line to afford proper

support for the track, are then braced as may be necessary to afford the requisite stiffness and resistance to horizontal thrusts. They 55 are then ready to receive the rails, one track being laid on the upper cross-pieces and the other near the inner ends of the projecting pieces below them. One track is therefore directly below the other, an opening being 60 left between the ends of the supports for the lower rail the whole length of the track. Through this opening pass chains by which the log is suspended from a car traveling upon the lower line of rails. When the end of the 65 line is reached, the car is run upon a switch, the free end of which has a vertical movement, thus enabling the car to be transferred from one line of rails to another. A stationary engine is used to give motion to an end- 70 less cable, one part of which travels along the lower and the other part along the upper tracks. The cars are provided with gripping devices which take a firm hold of the cable and are automatically released when the car 75 reaches its destination.

The number of cars used may be increased or diminished to suit the work to be done, their connection with the cable being such that they may be readily attached to the same 80 or detached therefrom without stopping its movement.

In the accompanying drawings, which fully illustrate the construction of the railway and the mechanism by which it is operated, 85 Figure 1, Sheet 1, and Fig. 1^a, Sheet 2, represent a plan view of the railway and the operating mechanism. Fig. 2, Sheet 1, and Fig. 2^a, Sheet 2, is a side elevation illustrating the relative arrangement of the supporting-frame 90 and track and vertical switches. Fig. 3 shows a plan of a portion of the track on a curve, illustrating the arrangement of sheaves for supporting the cable with relation to said track. Fig. 4 is a transverse vertical section 95 showing the relative positions of the tracks and the cars or trucks thereon. Fig. 5 is an enlarged view of the supporting-frame, tracks, and truck with a log suspended therefrom. Fig. 6 is a side elevation of the car and the 100 gripping mechanism by which it is connected with the cable. Fig. 7 represents a plan view of the car and gripping devices.

In these figures, A represents the posts or

uprights of the trestle; B, the caps or cross-pieces at the top of the same. The posts may be of round timber and the caps formed of a single piece resting on top of the posts, 5 or, as is considered preferable, of two pieces, one upon each side, securely bolted to said post. At suitable distances below the caps B are placed the lower track-supports C C, their outer ends bolted to the posts and their 10 inner ends supported by the rods *a* from the caps. Upon these supports are laid the rails *b b*, which support the car when loaded, the rails *b' b'*, carried upon the caps B, forming the return-track for the unloaded cars. The 15 length of the posts A of the trestle is varied to suit the undulations of the ground on the line of road and keep the tracks on a proper grade. Longitudinal braces, as *c c*, may be placed as needed between the trestles to 20 secure the proper rigidity of the structure.

The means preferably employed for propelling the cars on this road is an endless cable D, put in motion by steam or other power engine located at a suitable point on 25 the line, commonly one end of the same, the necessary traction being secured by passing the cable around a series of sheaves or pulleys E, which are geared together and to the engine in such a manner as to give to their 30 peripheries the same speed. From this traction apparatus the cable passes over suitable guide-pulleys F and F' to the two lines of track and along the same to the opposite end of the road, where similar guide-pulleys are 35 used to direct the cable from one track to the other. In passing curves a series of guide-pulleys, as G G, mounted upon vertical axles, are placed short distances from each other along the inner side of the curve and serve 40 to retain the cable in its proper position, as shown in Fig. 3 of the drawings, in which figure the track is shown with an offset to assist in carrying the cars by the pulleys which support the cable.

45 In order to transfer the unloaded car from the upper to the lower track a counterbalance-section H is hinged to the end of the upper track, forming a vertical switch, which acts automatically. The lower track below 50 the section H extends for something more than a car-length beyond the end of said section, forming the incline H'. As the car runs out upon the section H its free end goes down until it strikes upon the incline H', up which 55 the car runs until the switch is free, when it is instantly raised to its original position by the weight W upon the lever W', which is firmly secured upon the shaft I, forming the journal to which the section H or switch is 60 pivoted. The car is then free to run down the incline upon the lower track into position for loading or starting upon its return trip. On reaching the opposite end of the track and unloading the car it becomes necessary to raise it from the lower to the upper 65 track. This is accomplished by providing the section of track J, pivoted at J' upon a

supplementary trestle in such a manner that the end adjacent to the main tracks may be raised or lowered to come in alignment with either. The section of track may be wholly or partly balanced upon its pivot, and is raised from the lower to the upper line by means of the winch K after a car has been run upon it. The car may then be run upon the upper track and connected with the cable to be carried to the opposite end of the road.

The car used upon this road for the transportation of logs is of very simple construction, consisting of a pair of axles L L, provided with suitable wheels, said axles supporting and being connected by a beam M, upon the upper side of which is placed a gripping mechanism by which it is connected with the cable. This mechanism consists of 85 a fixed part or jaw N, securely bolted to the beam M, and a movable jaw N', pivoted to the part N. Each of these jaws are provided with a box-like receptacle, in which is placed the gripping-blocks *o o*, held in place and 90 adjusted by the screws *o' o'*. These gripping-blocks are preferably formed of some hard wood and may be easily replaced by others when worn out. They are provided with shallow grooves in their contiguous 95 faces, which grooves receive the cable. The pivoted jaw N' has a rearward extension N'', forming a lever for operating the jaw. As this lever is necessarily restricted in length and it requires considerable pressure to enable the jaws to get a secure grip of the cable, a shaft P is placed at right angles to the jaw and above the lever. This shaft carries a cam P', which cam, when the shaft is turned, 100 acts on the lever, causing the jaws to open or close. A wear-piece *x* is secured upon the lever N'', directly under the cam, and is made adjustable by means of a set-screw to take up the wear of the cam. This piece *x* is also so arranged as to admit of ready replacement 105 by a new one when necessary.

To the outer end of the shaft P is attached a lever R, carrying at its outer extremity a wheel R', by which it may be operated as it comes in contact with the incline *d d'* and *e e'* at the points where the car is to stop or start, the inclines *d* and *d'*, closing the grip upon the cable, thus starting the car and the inclines *e e'* in a reverse position, releasing the grip when it is desired to stop the 110 car.

The conical sheaves or pulleys S S, having upon their peripheries a groove, are placed upon the car at the opposite end of the gripping-jaws and serve as guides for the cable, 115 and a box T, for carrying chains, tools, or other articles, may be placed beneath the beam between the axles.

In Fig. 5 of the drawings is represented the method of suspending the log beneath 120 the car for transportation. Chains *m m* are attached to straps *m'*, which pass over the beam M, and are provided with hooks at each end. To these chains *m* the chains *n n*,

which pass around the log and are provided with dogs to drive into the same, are secured. One of these dogs has a handle-like extension, a blow upon which dislodges the dog 5 when it is desired to unload and allows the log to fall.

In operating this road the car connected with the cable on the upper track proceeds to the place where it is to receive its load, and 10 when it arrives at the incline marked "Stop" in Fig. 1 the grip will be released by the action of said incline on the lever R. The car will then proceed slowly onto the hinged section of track H. The weight of the car will 15 press said section down until the ends come in contact with the inclined portion H' of the lower track. The car continues its way, and when clear of the tipping-section H the latter will at once be raised by the weight W, 20 and the car will run down the incline H' until it strikes the stop c'. It is now in position to be loaded, after which, the stop being removed, the car runs forward on the track, the grip-lever strikes the incline d', which causes 25 the grip to seize the cable, and the car continues its course to the opposite end of the track, where it is to be unloaded. Upon reaching this point the grip-lever comes in contact with the incline e, the cable is released, and the 30 car is stopped. The log is then disengaged from the chains, and the car moved forward upon the pivoted track J, where it is held by the stop i. The winch K or other suitable mechanism is then used to raise the track J 35 to a level with the upper line of rails. The car runs off upon said line, and the grip-lever strikes the incline d, causing the gripping-jaws to grasp the cable, and the car proceeds on its way to the opposite end of the 40 line for another load.

We are aware that elevated railways have been devised with two tracks, one above the other; but such roads were intended for use with a double system of cars, those upon the 45 upper tracks being mounted upon their trucks

in the ordinary manner, while those intended for use upon the lower track were suspended from the truck beneath the track. We do not, therefore, broadly claim an elevated railway having two tracks, one above the other, 50 but limit our claims to the construction and arrangement of parts hereinbefore described.

Having thus described our invention, we claim as new, and desire to secure by Letters Patent, the following:

1. As an improvement in elevated railways, the combination of the two tracks, one placed directly above the other, with the vertically-acting switches adapted to transfer the cars from one track to the other, as specified. 55

2. As an improvement in elevated railways having two tracks, one above the other, the combination, with said tracks, of the hinged counterbalanced section H and the inclined section H', arranged substantially as shown 60 and described.

3. As an improvement in elevated railways having two tracks, one above another, the combination, with said tracks, of the pivoted section J and the winch K, adapted for raising 65 said section from the lower to the upper track, as set forth.

4. As an improvement in elevated railways and devices for operating the same, the combination of two tracks placed one above the 70 other, an endless cable and mechanism for operating the same, a car provided with a gripping device for attaching the car to the cable, and inclines in a fixed position adapted to automatically close and open the gripping-jaws upon the approach of the car, substantially as shown and described. 75

In testimony whereof we affix our signatures in presence of two witnesses.

ALEXANDER RODGERS.
GILBERT MEE.
